UNITED STATES PATENT OFFICE.

JOHN PICO, OF FORT LOGAN, MONTANA.

COMBINED CAN OPENER, SEALER, AND HANDLE.

Application filed June 7, 1928. Serial No. 283,553.

The invention provides an implement adapted for use in puncturing a can to admit of pouring off the liquid contents, for sealing the punctures to exclude air and prevent entrance of foreign matter, and for convenience of handling the can when dispensing its contents.

The invention aims to supply a device of the character aforesaid which is simple, easily applied, readily adjusted to the required position and capable of being made secure in the adjusted location.

While the drawing illustrates a preferred embodiment of the invention, it is to be understood that in adapting the means to meet specific needs and requirements, the design may be varied and such other changes in the minor details of the invention as claimed, without departing from the spirit thereof.

For a full understanding of the invention and the merits thereof, reference is to be had to the following description and the drawing hereto attached, in which:

Figure 1 is a perspective view illustrative of an application of an embodiment of the invention.

Figure 2 is a detail sectional view on the line 2—2 of Figure 1 looking in the direction of the arrows.

Figure 3 is a view similar to Figure 2 showing the device in position with the spurs penetrating the top of the can.

Corresponding and like parts are referred to in the following description and designated in the several views of the drawing by like reference characters.

The numeral 1 denotes a can such as generally provided for receiving a liquid commodity, such as evaporated milk, or cream, syrup and the like, which is adapted to be dispensed by perforating the top of the can for the outflow of its liquid contents and the inflow of air to replace the out-flowing contents. The device will be provided in sizes best adapted to the size of can for which it is particularly adapted. The device includes a frame 1' to receive an end portion of the can, as indicated in the several views. The frame comprises a cross bar 2 and depending side bars 2'. Spurs 3 depend from end portions of the cross bar 2 of the frame and are adapted to puncture the top of the can 1 ad-

jacent opposite sides, as indicated at 4. Soft rubber washers 5 are slipped upon the spurs 3 and operate as closures to seal the openings 4 when the can is not required for immediate use, thereby excluding air and preventing any foreign matter from finding its way into the can, when set aside. A clamp band 6 of a size to encompass the can 1 is secured to the lower ends of the side bars 2' of the frame. The band 6 usually consists of a metal strap which after being bent into circular form to embrace the can has its ends offset and apertured to receive a bolt 7 and thumb nut 8. The handle 9 is secured at one end to the cross bar 2 of the frame 1' and at its opposite ends to the clamp band 6 adjacent an offset end thereof. The parts do not interfere with the resiliency of the band 6 so that it may be adjusted easily upon the can to the required position.

When it is required to pour off the liquid contents of a can the device is slipped upon an end thereof substantially as indicated in Figure 1 of the drawing and pressure is applied to the cross bar 2 of the frame 1' in a manner to cause the spurs 3 to penetrate the top of the can after which the device is lifted to withdraw the spurs 3 from the punctures 4. The device is now turned upon the can to bring the handle 9 in line with the punctures 4 and is made secure by turning up the thumb nut 8 thereby contracting the band 6 and causing it to grip the sides of the can 1 with sufficient force to hold the device in fixed position. By grasping the handle 9 and tilting the can the contents thereof will flow through the lower opening 4 and air will enter the upper opening. When the can is to be set aside the clamp band 6 is loosened by backing the thumb nut 8 thereby admitting turning of the device upon the can to bring the spurs 3 in registering position with the openings 4 when pressure is exerted upon the cross piece of the frame 2 to cause the spurs 3 to enter the openings 4 and the washers 5 to seal said openings and prevent the entrance of air therethrough or the passage of dust or other foreign matter into the can. The position of the device is fixed by retightening the thumb nut 8 thereby causing a contraction of the band 6 and a clamping of the can thereby.

Having thus described the invention, I claim:

A combined can perforator, sealer and handle comprising a frame including a cross bar and depending side bars, spurs adjacent opposite ends of the cross bar of the frame, a clamp band consisting of a metal strap bent into circular form and having its end portions offset and perforated to receive a

bolt and nut, and having the side bars of the frame connected thereto at opposite sides of the offset ends of the band, and a handle connected at one end to the cross bar of the frame midway the ends thereof, and having its opposite end connected to the clamp band adjacent an offset end thereof.

In testimony whereof I affix my signature.
JOHN PICO. [L. S.]
